SUCTION BRUSH FOR CLEANING
VENETIAN BLINDS

Joseph P. Zaidan, Philadelphia, Pa.

Application June 6, 1950, Serial No. 166,388

1 Claim. (Cl. 15—394)

1

This invention relates to a cleaner for Venetian blind slats.

An object of this invention is to provide a cleaner in the form of a brush head adapted for connection with a vacuum cleaner for cleaning opposite sides of a Venetian blind slat.

Another object of this invention is to provide an improved suction head which includes a pair of brushes formed with longitudinal slots so that air may be drawn through the slots with dust or dirt which is picked up by the suction head.

A further object of this invention is to provide an improved suction head wherein the brush members are readily removable for cleaning, replacement or the like.

A further object of this invention is to provide a suction head for attachment to a vacuum cleaner including an opposed pair of brushes, the head being of simple construction so that it can be produced at relatively small cost.

With the above and other objects in view, my invention consists in the arrangement, combination and details of construction disclosed in the drawings and specification, and then more particularly pointed out in the appended claim.

In the drawings:

Figure 1 is a plan view of a Venetian blind slat cleaner constructed according to an embodiment of this invention.

Figure 2 is a sectional view taken on line 2—2 of Figure 1.

Fig. 3 is a sectional view taken on the line 3—3 of Figure 2.

Fig. 4 is a sectional view taken on the line 4—4 of Figure 3.

Figure 5 is a plan view of one of the brush elements.

Referring to the drawing, the numeral 10 designates generally a suction head which is formed of an elongated body 11 provided with a transverse slot 12 within which a Venetian blind slat is adapted to loosely engage. The body 11 is provided with a pair of openings 13 extending lengthwise of each arm 14 thereof and opening inwardly. The openings 13 extend rearwardly and communicate with the interior 15 of a nipple 16 which extends from the rear of the body 11. The nipple 16 is adapted to be connected in a conventional manner to the flexible hose of a vacuum cleaner.

A pair of brush members generally designated as 17 are removably mounted in lengthwise extending channels 18 formed in the arms 14, and each brush member 17 is formed of an elongated back 19 which is provided with a longitudinally extending slot 20. A pair of bristle rows 21 are disposed on each side of the slot or opening 20, and the brushes are disposed with the bristles in

2

confronting position for engagement on the opposite sides of a Venetian blind slat.

The longitudinal opening 20 in each brush provides for pulling dust or dirt through the brush back 19 as the brushes are moved lengthwise of a slat. Each brush back 19 is provided at its outer end with a lug 22 which is engageable with the outer end of an arm 14 to limit the inward extension of the brush and also provide a means whereby the brush may be readily removed for cleaning, replacement, or the like.

In the use and operation of this device the suction head 10 is connected by means of the nipple 16 to a flexible hose which is connected to a vacuum cleaner. The brushes 17 are extended transversely across the Venetian blind slat, and the head is then moved lengthwise of the slat. The dust or dirt removed by the bristles of the brushes will be drawn through the head 10 into the collector of the vacuum cleaner.

This device may be made out of any suitable material and can be produced as an attachment for vacuum cleaners of various types.

What is claimed is:

25 A Venetian blind slat cleaner comprising a head member formed of a body, a pair of parallel arms extending from one end of said body, a coupling nipple extending from the other end of said body, said arms and body having passages communicating with said nipple, each arm having a longitudinal channel opening through the outer end thereof, an opposed pair of brushes 30 each formed of a rigid back engaging in one of said channels, each back having a longitudinal slot, bristles carried by each of said backs on opposite sides of each slot and a lip carried by the outer end of each back engaging against the outer end of an arm, said lip constituting a stop and also providing means whereby said brushes 35 may be withdrawn from said channels.

JOSEPH P. ZAIDAN.
